United States Patent Office

Des. 184,990
Patented Apr. 28, 1959

184,990

CART

Leopold Durko, Morton Grove, Ill., assignor to Comfort Lines, Inc., Chicago, Ill., a corporation of Illinois

Application March 21, 1958, Serial No. 50,135

Term of patent 14 years

(Cl. D33—14)

The figure is a perspective view of a cart embodying my new design.

I claim:

The ornamental design for a cart, substantially as shown.

References Cited in the file of this patent

UNITED STATES PATENTS

D. 148,706 Kenney ----- Feb. 17, 1948

1,752,687 Newhouser ----- Apr. 1, 1930
2,482,230 Welsh ----- Sept. 20, 1949

OTHER REFERENCES

Gift and Art Buyer, October 1954, page 65, Cart, bottom of page.

Gift and Art Buyer, January 1957, page 9, Bar Cart, upper left of page.